UNITED STATES PATENT OFFICE.

JASPER WILLIAM WOOD, OF NEEDLES, CALIFORNIA, ASSIGNOR OF FORTY-FIVE ONE-HUNDREDTHS TO THOMAS J. MURPHY AND TEN ONE-HUNDREDTHS TO FREDERICK C. BLODGETT, OF NEEDLES, CALIFORNIA.

CYLINDER-DRIVE ENGINE.

1,190,838.

Specification of Letters Patent. Patented July 11, 1916.

Application filed January 5, 1914. Serial No. 810,521.

To all whom it may concern:

Be it known that I, JASPER W. WOOD, a citizen of the United States, residing at Needles, in the county of San Bernardino and State of California, have invented a new and useful Cylinder-Drive Engine, of which the following is a specification.

This invention relates to internal combustion engines in which the engine transmits its power from the cylinder instead of from the pistons.

An object of the invention is to provide an arrangement whereby to increase the efficiency of the internal combustion engine and to decrease the fuel consumption of the same. To these ends the engine is mounted to transmit its power in a direct line against the cranking shaft which is made possible by mounting the cylinder of the engine to oscillate so as to transmit the power of the engine from the cylinder instead of from the pistons.

A further object of the invention is to provide a fuel feed into the firing and compression chambers of the cylinder; and this is done through a channel formed inside of the pistons of the engines and the cross head connected to the pistons about which the oscillating cylinder is adapted to rock.

With respect to this feature of the invention a carburetor is attached to the cross head or shaft to which the pistons are connected.

It is a still further object of the invention to provide an engine in which the engine member will operate with the least resistance due to friction caused by side thrust or the like. This is accomplished by permitting the piston member and cylinder to operate relative to one another in a direct line, which particularly distinguishes it from a piston member connected to an eccentric.

Another object of the invention is to provide an engine which is substantially free from liability to knocks. To this end adequate air cushions are provided in which the piston member operates.

Still another object of the invention is to provide a self-air-cooling engine.

Other objects of the invention are cheapness and simplicity of construction, minimum number of parts, minimum amount of machine work, ease and convenience of assembling and repairing and minimized liability of getting out of order.

The engine is provided with two cylinders fixed together and two pistons fixed together, the cylinders working on the pistons and connected to a crank shaft.

The particular feature of invention resides in the novel means of supplying fuel to the firing chambers of the cylinders. This is effected through the pistons and the piston rod or rods connecting said piston, the same being provided with a channel that communicates at its ends alternately with by-pass passages in the cylinders; the arrangement being such that at the end of the compression stroke of one piston, fuel passes through such piston and the by-pass into the compression chamber for such piston while the by-pass into the combustion chamber for the other piston is closed by such other piston; and the exhaust port from the combustion chamber of the other piston, and a fuel passage into the combustion chamber of such other piston from the compression chamber therefor, are open; and vice versa, at the next stroke.

The features, capabilities and advantages of the invention will become apparent from the subjoined detail description of one specific embodiment thereof.

The invention is illustrated in the accompanying drawings.

Figure 1 is a plan showing the cylinder drive engine mounted in position for use. Fig. 2 is an elevation in section on line x^2-x^2 , Fig. 1. Fig. 2^a is an end elevation of the intermediate body portion viewed from line 2^a-2^a , Fig. 2. Fig. 3 is an enlarged fragmental elevation in section on the staggered line x^2-x^3 of Figs. 1 and 5. Fig. 4 is an elevation of one cylinder in section on line x^4-x^4 , Fig. 1, looking in the direction of the arrow. Fig. 5 is an elevation on line x^5-x^5 of Figs. 1 and 2, looking in the direction of the arrow.

In the embodiment shown a frame comprising two rails 1, 1, is provided with cross head bearing portions 2, 2, to support the cross head 3 on which the cylinder is slidably, and by which it is pivotally, mounted to oscillate and rock. The rails 1, 1 are also provided with crank shaft bearing portions 4, 4 to support the crank shaft 5. The bearing portions 2, 2 and 4, 4 are in fixed relation to each other and the rails. The cross head 3 is provided with a threaded transverse recess 6 to receive the inner

threaded ends of piston rods 7, 7, which are screwed into the opposite ends of the recess 6 and come into contact with one another at substantially the middle of the recess 6. 5 The piston rods are thus made oscillatory upon an axis that is in fixed relation to the axis of the crank shaft.

The piston rods 7, 7 are connected with piston heads 22, 22 that operate in a double cylinder 8 to form firing chambers 9, 9, one at each end of the cylinder 8. The cylinder is preferably composed of three portions; there being two end body portions 10, 10 and an intermediate body portion 11. The end body portions 10, 10 are each provided with suitable flanges 12, 12 to fit against corresponding flanges 13, 13 of the ends of the intermediate body portion 11 to form one continuous cylinder. The exterior end of one 10 of the body portions 10 of the cylinder 8 is provided with an extension 14 integral with said body portion to form a seat for a suitable securing portion to which the crank arm 15 of the crank shaft 5 may be pivoted, 15 as for instance, (see Fig. 2) two bearing blocks 16, 16 provided with recesses to form a circular opening to receive the crank arm 15 as shown, said blocks being held in place against the T-shaped extension 14 by means 20 of the U-shaped binding rod 17 which is suitably bolted to the extension.

By means of its body wall the intermediate body portion 11 of the cylinder 8 forms a longitudinal guide-way 18 running substantially through the entire middle of said body portion, the guide-way being adapted to receive the cross head 3 to permit the cylinder 8 to slide on said cross head when in operation. The intermediate body portion 35 40 11 forms with the end body portions 10, 10 compression chambers 19, 19, one for each piston, the chambers being separated from one another by partitions 20, 20, guide extensions 20' thereof, glands 41 and piston rods 7 working therein.

Each of the piston rods 7, 7 is provided with a diminished end portion 21 which forms a shoulder with the main body portion of its piston rod 7, the extreme end portion 50 of the diminished portion 21 being screw-threaded. Piston heads 22, 22, each of which has an internal opening, having an enlarged portion 23 to fit upon the main body portion of the piston rod 7 and a diminished portion 24 to fit the diminished portion 21 of the piston rod 7, are adapted to be secured onto the ends of the piston rods 7, 7, being limited in their inward movement by the shoulders formed by the 55 diminished body portions 21, 21 and diminished openings 24, 24. The piston heads have recesses 25, 25, surrounding their diminished openings 24, 24, so that when the piston heads are mounted onto the piston rods, nuts 26, 26, which secure the piston

heads from outward movement, being screwed onto the screw-threaded ends of the diminished body portions 21, 21, will be located in their recesses 25, 25. Cotter pins 27, 27 are provided to secure the nuts 26, 26 from movement. 70

The vaporized or other gaseous fuel is conveyed to the compression and firing chambers from the fuel source through the cross head 3, piston rods 7, 7 and heads 22, 22. In Figs. 1 and 5 there is shown suitably mounted on one of the rails 1 adjacent to the bearing portion 2, a housing 28 to which a carbureter 29 is connected. The cross head 3 is provided with an internal channel 80 or chamber 30, and the piston rods are provided with internal channels 31, 31 and with a port 46 to form a communication between the carbureter 29 to supply fuel to the internal channels 31, 31, formed in the piston rods 85 7, 7. The piston rods thus together form a tubular connection from one piston head to the other. A suitable packing gland 32 is provided where the carbureter makes its connection with the channel 30. 90

To convey fuel from the channel 31 to its adjacent compression chamber 19 a passage 33, communicating with channel 31, is provided in each piston head, which effects intermittent communication to its adjacent 95 chamber 19 by means of a bent or U-shaped channel having an inlet 34 and an outlet 35 spaced apart longitudinally of the cylinder. The respective body portions 10, 10 may bulge out to accommodate the U-shaped 100 channels as shown in Figs. 1, 2 and 3. This intermittent communication is effected for either piston when its piston head is in a position nearest to the outer end of the body portion 10 of the cylinder in which it operates. In this position, as shown by the right hand piston head in Fig. 2, the passage 33 registers with the inlet 34, and the outlet 35 opens into the compression chamber 19. As firing takes place in the firing 110 chamber 9 the adjacent end portion 10 of the cylinder is driven away from its piston head whereby as shown in the left hand side of Fig. 2 the feeding communication to its compression chamber 19 is cut off. 115

Similar to the compression chambers, when feeding fuel to the firing chambers, one is first fed and then the other, the feeding to the firing chamber 9 of either piston head taking place when the feeding to the 120 compression chamber of such piston head is cut off, and vice versa. As shown in Fig. 3, when firing has taken place at one end of the cylinder, and that end of the cylinder is in a position away from the piston head 125 22, communication is made between the firing chamber 9 and the compression chamber 19 by the L-shaped passage having an inlet 37 and an outlet 38. The outer wall 39 of the L-shaped passage bulges outwardly from 130

the main contour of its end body portion 10. As the fuel rushes into the firing chamber through the outlet 38 it will strike a deflector 40 which is provided to direct such fuel into the chamber 9. A deflector 40 is 5 provided on the face of each piston head 22.

To prevent leakage from the compression chambers 19, 19 through the operation of the piston rods, suitable packing glands 41, 10 41 are provided which are located, one at each end of the guide way 18.

Spark plugs 42, 42 are provided projecting into the firing chambers 9, 9, in the usual manner, the spark plugs having a wire 15 connection with contact members 43, 43 provided on the outside of the end body portions 10, 10. On the rails 1, 1, preferably on one of them, as shown in the present instance, contact members 44, 44 are provided 20 in position to alternately contact with the contact members 43, 43, respectively, on the outside of the end body portions. The arrangement is such that when the cylinder 8 is oscillated in one direction, one set of contact 25 members will register to fire one end of the cylinder, and when oscillated in the other direction, the other set of contact members will register to fire the other end of the cylinder. The contact members 44, 30 44 are adjustably mounted to facilitate adjusting for various causes.

Openings 45, 45, are suitably located, one for each firing chamber 9, to pass off the exhaust.

35 It is obvious that various changes and modifications may be made in the details of construction without departing from the general scope of the invention.

I claim:

1. A cylinder having a piston head in each end and together with said heads forming firing chambers and compression chambers on opposite sides of said heads respectively and a tubular connection slidably 40 mounted in and relative to the cylinder and extending from one head to the other head and provided with a port, a pivotally mounted cross head fastened to the tubular connection and having an internal chamber 45 communicating with said port; a carburetor connected to the chamber of the cross head, and means to first pass fuel from said tubular connection to one of the compression chambers and from the other compression 50 chamber to one of the firing chambers and to then pass fuel from said tubular connection to the other compression chamber and from the first compression chamber to the other firing chamber.
2. A cylinder having a piston head in each end and together with said heads forming firing chambers and compression chambers on opposite sides of said heads, a tubular connection from one head to the 55 other head, means slidably mounting said

tubular connection in and relative to the cylinder, means to supply fuel to said tubular connection, and means to first pass fuel from said tubular connection to one of the compression chambers and from the other compression 70 chamber to one of the firing chambers and to then pass fuel from said tubular connection to the other compression chamber and from the first compression chamber to the other firing chamber.

3. A frame, a cross-head pivoted on the frame and provided with an internal chamber, a carburetor connected to said chamber, a tubular connection connected to the cross-head and provided with a port communicating with said chamber of the cross-head, and a cylinder having a piston head in each end and together with said heads forming firing chambers and compression chambers on opposite sides of said heads, said heads having passages communicating with the tubular connection and said cylinder being provided with channels each having an inlet and an outlet, said inlets communicating with said passages and said outlets communicating alternately with the compression chambers.

4. In an internal combustion engine the combination with a frame, a cross head mounted to rock on said frame, a pair of 95 axially alined pistons fixed to said cross head to rock therewith, a cylinder mounted outside of said pistons to slide relative to said pistons, means for producing fluid expansion for actuating said cylinder, and a 100 driven member connected to said cylinder to be driven thereby when said cylinder is actuated.

5. In an internal combustion engine the combination with a frame, a cross head 105 mounted to rock on said frame, a pair of piston rods fixed to said cross head to rock therewith, a cylinder mounted outside of said piston rods and adapted to slide relative to said piston rods, piston heads on said 110 piston rods to form compression and firing chambers in said cylinder, means for feeding fuel to said firing chambers, and means for igniting said fuel to actuate said cylinder.

6. In an engine the combination with a frame, a cross head mounted to rock on said frame, a pair of piston rods fixed to said cross head to rock therewith, a cylinder mounted outside of said piston rods and adapted to slide relative to said piston rods, piston heads on said piston rods to form compression and firing chambers in 120 said cylinder, passages formed in said cross head, piston rods, piston heads, and cylinder 125 communicating with said firing chambers to supply fuel to said firing chambers, and means for igniting said fuel in said firing chambers to actuate the cylinder.

7. In an internal combustion engine the 130

combination with a frame, a cross head mounted to rock on said frame, a pair of piston rods fixed to said cross head to rock therewith, a cylinder mounted outside of said piston rods and adapted to slide relative to said piston rods, piston heads on said piston rods to form compression and firing chambers in said cylinders, passages formed in said cross head, piston rods and 10 piston heads communicating with said compression chambers to supply fuel to said compression chambers, means for supplying said fuel to the firing chambers from the compression chambers, and means for igniting 15 the fuel in said firing chambers to actuate the cylinder.

8. In an internal combustion engine the combination with a frame, a cross head mounted to rock on said frame, a pair of piston rods fixed to said cross head to rock therewith, a cylinder mounted outside of said piston rods and adapted to slide relative to said piston rods, compression and firing chambers formed in said cylinder, a 20 passage formed in said cross head, a carburetor fixed to said frame and adapted to communicate with the passage in said cross head to feed fuel into the passage, passages formed in said piston rods communicating 25 with said cross head to feed said fuel from said cross head into said compression chambers, means for conveying said fuel from said compression chambers to said firing chambers, and means for igniting the fuel 30 in said firing chambers to actuate the cylinder.

9. In an internal combustion engine, the combination with a frame, of pistons mounted to rock on said frame, a cylinder mounted outside of said pistons and adapted to slide relative to said pistons to form compression and firing chambers in said cylinder, and passages in said pistons through 45 which to feed fuel to said compression chambers.

10. In an internal combustion engine, the combination with a frame, of a pair of pistons mounted to rock on said frame, a cylinder mounted outside of said pistons and 50 adapted to slide relative to said pistons to form compression and firing chambers in said cylinder, and means for feeding fuel to said firing chambers.

11. In an internal combustion engine having an oscillating cylinder, pistons mounted inside of said cylinder and adapted to slide relative to said cylinder to form compression chambers and firing chambers in said cylinder, and passages in said pistons to feed fuel 55 to said compression chambers.

12. In an internal combustion engine, the

combination with a pivoted cylinder, axially aligned pistons mounted to slide relative to said cylinder to form compression and firing chambers in said cylinder, means for feeding fuel to said compression chambers, means for feeding fuel from said compression chambers to said firing chambers, and means for igniting said fuel in said firing chambers. 65

13. In an internal combustion engine, the combination with a pivoted cylinder, axially aligned pistons mounted to slide relative to said cylinder to form compression and firing chambers in said cylinder, 70 passages in said pistons, passages in the cylinder alternately affording communication between the passages in said pistons and said compression chambers and between the compression chambers and the firing chambers, 75 said communications being adapted to permit fuel to be alternately fed to said compression and said firing chambers as set forth, and means for igniting the fuel in said firing chambers. 80

14. In an internal combustion engine, the combination with a pivoted cylinder, axially aligned pistons mounted to slide relative to said cylinder to form compression and firing chambers in said cylinder, and 85 means for feeding fuel to said firing chambers, said means comprising passages in said pistons, passages in the cylinder alternately affording communication between the passages in said pistons and the compression chambers and between the compression chambers and the firing chambers, and 90 means for igniting the fuel when in said firing chambers. 95

15. An internal combustion engine having 100 a compression chamber, a piston and piston rod having an internal passage through which fuel is supplied to such chamber, and a pivotally mounted cross head having a chamber communicating with said passage. 105

16. An internal combustion engine having a compression chamber and a firing chamber, a piston head and piston rod having intercommunicating passages through which fuel is supplied to the compression chamber, 110 and a pivotally mounted cross head having a chamber communicating with the passage in the piston rod, and means to transfer the compressed charge from the compression chamber to the firing chamber. 115

In testimony whereof, I have hereunto set my hand at Los Angeles, California, this 13th day of December, 1913.

JASPER WILLIAM WOOD.
